UNITED STATES PATENT OFFICE.

CHARLES B. EASTMAN AND MINOT C. EASTMAN, OF GEORGETOWN, MASSACHUSETTS.

FIRE-ALARM.

1,187,982.

Specification of Letters Patent. Patented June 20, 1916.

Application filed April 7, 1915. Serial No. 19,780.

To all whom it may concern:

Be it known that we, CHARLES B. EASTMAN and MINOT C. EASTMAN, citizens of the United States, residing at Georgetown, 5 in the county of Essex and State of Massachusetts, have invented certain new and useful Improvements in Fire-Alarms; and we do hereby declare the following to be a full, clear, and exact description of the invention, such as will enable others skilled in the art to which it appertains to make and use the same.

This invention relates to new and useful improvements in automatic fire alarms.

15 The principal object of the invention is to provide means to indicate fire in any part of a building by means of electric connections.

Another object of our invention is to provide 20 a device of the above character which may be connected to signal in several different places at the same time, should a fire occur in any part of a building.

Another object of our invention is to provide 25 a casing having a source of electrical supply and the contact points therein, thus forming a compact device which may be located at any desirable point.

With the above and other objects in view, 30 we will now proceed to describe our invention in the following specification and accompanying drawings, in which,

Figure 1 is a front view in elevation of the casing and interior mechanism for the alarm 35 with the cover removed, Fig. 2 is a vertical sectional view through the circuit closing section of the casing, illustrating the detail construction of the circuit closer, Fig. 3 is an enlarged transverse sectional view 40 through the casing, Fig. 4 is a detail view in elevation of one of the pulleys used in connection with the device, and Fig. 5 is an edge view of said pulley.

Referring to the drawings by characters 45 of reference, 1 indicates generally the casing forming the main part of our improved fire alarm. This casing preferably comprises the end walls 2, the side walls 3, the bottom 4 and the cover 5. Intermediate the side 50 walls, we preferably provide a division wall 6, which separates the battery section from the contact section. This wall 6 extends longitudinally through the middle of the box and throughout its entire length.

55 A source of electrical supply, preferably batteries indicated at 7 and 8, respectively,

is provided and the current from this source of supply passes through the switch indicated generally at 9, which may be of any preferred type.

60 The circuit closing mechanism of our improved fire alarm preferably comprises a longitudinally slidable member 10 which is provided at each extremity with the L-shaped portions 11, these portions 11 being adapted to limit the longitudinal movement of the slide 10 by coming in contact with the transverse strips 12 secured to the bottom 4 of the box. A sliding block 13 is fixedly mounted upon the slide 10 and is provided upon its upper side with a cam surface 14 preferably segmental in contour and provided with a metallic plate 15. Each metallic plate 15 is adapted to contact at either end with a spring 16, through which the current on its way through the circuit closer passes. Each spring 16 co-operates with a plate 17, against which the finger 18 of the spring is pressed, by means of the metallic plate 15 carried on the sliding block 70 13. The ends of the sliding block are preferably recessed, as clearly illustrated at 19 and adapted to receive the ends 20 of the springs 21.

75 A suitable pin 22 passes transversely through each recess 19 and is adapted to extend slightly beyond the extremity of the block 13 and into an aperture formed in the sliding member 10 as clearly illustrated in Fig. 2. This pin 22 is adapted to be surrounded by the end 20 of the spring 21 and hold the spring in operative relation to the sliding block 13. The end of the spring 21 opposite the end 20 is preferably provided with an eye 23 which is adapted to receive the end of the cord 24, by means of which the device is actuated. The cords 24 extend out of the box, as is clearly illustrated, and pass over the pulleys, indicated 85 generally at 25, these cords being adapted to enter different parts of the building and have weights attached to their ends, by means of which they are kept at all times taut, so that at any time, should any cord extending from the springs 21, pulling against the tension of the weights be burned, said cord will be released and cause the sliding block of the circuit closer to press the spring fingers of the member 16 forward and into contact with the plate 17, thereby completing the circuit to cause the 90 95 alarm bell to ring. The pulleys referred to

100 105 110

generally as 25, are clearly illustrated in Figs. 4 and 5, and preferably comprise the body portion 26, having formed at one extremity thereof a point 27 which is adapted to be driven into the wall of a building. The opposite terminal of the body portion 26 is bent back upon itself, as clearly illustrated at 28, and forms a U-shaped member, as clearly shown in Fig. 5, between which the pulley 29 is rotatably mounted on its axle 30. A suitable aperture 31 is provided in the portion 28 and is adapted to receive a nail or tack, by means of which the device is more securely held in place.

15 In use, the box 1 is placed at any desired point in a building and the cords 24 pass outwardly therefrom, these cords 24 being carried along the ceiling by means of the pulleys 25, and are provided at their terminals with suitable weights not shown which will keep the cords taut at all times and also keep the springs 21 extended. It will be clearly seen that, should a fire break out in any part of the building and the cord burn

20 through, the springs will cause the cord to be pulled, thereby causing the cam face of the sliding block 13 to force one of the fingers 18 of the spring 16 forward and in contact with the plate 17, thus completing

25 a circuit through the alarm bell and giving an alarm through the building.

It is to be understood that while we have shown and described a specific form of pulley adapted for use in connection with our fire alarm, we desire to retain the right to use any preferred type of pulley without departing from the spirit and scope of the invention.

The cords 24 are so treated with a suitable chemical or may be formed of a suitable composition which will enable them to readily burn, but which will prevent the fire from traveling along the cord and causing another part of the building to be ignited.

While in the foregoing we have shown 45 and described the preferred embodiment of our invention, we wish to have it understood that we may change the specific arrangements of parts without in any way departing from the spirit and scope of our 50 invention.

Having thus fully described our invention, what we claim is:

1. A device of the class described comprising a casing having openings in each 65 end, slides slideable longitudinally through the casing, cams on the upper sides of the slides, contact plates extending across the slides near each end and spaced upwardly therefrom, contact springs to engage the 70 plates to close an electric circuit, and springs normally under tension connected to each end of the slides to hold the slides centrally of the casing until the tension of one of the 75 springs is released.

2. A device of the class described comprising a casing having openings in each end, slides slideable longitudinally through the casing, cams on the upper sides of the slides, contact plates extending across the slides near each end and spaced upwardly therefrom, contact springs to engage the plates to close an electric circuit, springs normally under tension connected to each end of the slides to hold the slides centrally of the 80 casing, and flexible members of a readily combustible material connected to the springs and extending to different parts of the building, said flexible members holding the springs under tension.

In testimony whereof we affix our signatures in presence of two witnesses.

CHARLES B. EASTMAN.
MINOT C. EASTMAN.
